UNITED STATES PATENT OFFICE.

CHARLES J. OLSON, OF MUSKEGON, MICHIGAN.

ROTARY MOTOR.

992,582.

Specification of Letters Patent. Patented May 16, 1911.

Application filed November 3, 1908. Serial No. 526,010

To all whom it may concern:

Be it known that I, CHARLES J. OLSON, citizen of the United States, residing at Muskegon, in the county of Muskegon and 5 State of Michigan, have invented certain new and useful Improvements in Rotary Motors, of which the following is a specification.

This invention relates to rotary motors and has for its object to provide a strong, 10 durable, compact and thoroughly efficient machine of this character, capable of being operated by compressed air, steam, or other actuating fluid, and which may be used with equally good results for operating a pneumatic drill, or as a motor for driving different kinds of machinery.

A further object is to provide a rotary motor, the construction of which is such that the several parts thereof are evenly balanced, 20 thus insuring a smooth continuous movement of the rotors, and consequently increasing the efficiency of the machine.

A still further object of the invention is generally to improve this class of devices so 25 as to increase their utility, durability and efficiency.

Further objects and advantages will appear in the description, it being understood that various changes in form, proportions 30 and minor details of construction may be resorted to within the scope of the appended claims.

For a full understanding of the invention reference is to be had to the following 35 description and accompanying drawings, in which:

Figure 1 is a perspective view of a rotary motor constructed in accordance with my invention, showing the same used in connection 40 with a pneumatic drill. Fig. 2 is a vertical sectional view of the same. Fig. 3 is a transverse sectional view taken on the line 3—3 of Fig. 2 and looking in the direction of the arrow. Fig. 4 is a similar view taken 45 on the line 4—4 of Fig. 2 and looking in the direction of the arrow. Fig. 5 is an enlarged detail sectional view of a portion of one of the rotors and the adjacent side of the casing. Fig. 6 is a vertical sectional 50 view showing the construction of the motor when the latter is employed for driving different kinds of machinery.

Corresponding and like parts are referred to in the following description and indicated in all the views of the accompanying drawings by the same reference characters.

The improved motor forming the subject-matter of the present invention comprises a casing or housing 5 preferably substantially cylindrical in shape, and formed of a plurality of independent sections 6 held in assembled position by tie-rods or bolts 7 piercing the opposite heads 8 and 9 of the casing. 60

Interposed between the casing sections 6 are a plurality of transverse partitions 10 defining intermediate compartments 11 in which are mounted for rotation a plurality of rotors 12, the latter being keyed or otherwise fixed to a centrally disposed driving shaft 13. 70

The casing or housing 5 is provided with oppositely disposed enlargements 14, each pierced by an inlet port 15 and exhaust port 16, there being auxiliary ports 17 formed in suitable turning plugs 52' threaded in the 75 casing sections, and through which compressed air or other actuating fluid is admitted to the compartments 11. Auxiliary ports 18 are formed in the casing sections to permit the passage of the exhaust steam 80 from the compartments 11 to the ports 16 and thence through the opening or port 18' to the atmosphere.

The rotors 12 are preferably of irregular shape and are each provided with peripheral 85 recesses 19 in which are pivotally mounted at 20 blades or pistons 21, there being a shoulder 22 formed by one wall of each recess 19 for the purpose of limiting the swinging movement of the adjacent piston. The 90 pistons 21 are normally and yieldably supported in engagement with the interior walls of the casing or housing 5 by means of coil springs 23, one end of each of which is seated in a socket or depression 24 in the 95 rotor, while the other end thereof bears against the adjacent face of the piston, as best illustrated in Fig. 3 of the drawings, the outer ends of the pistons being inclined or beveled at 25 to permit the latter to conform to and bear against the inner wall of the casing. Secured to the outer face of each piston 21 is a metallic plate 26 having its opposite ends deflected upwardly at 27 for yieldable engagement with the inner 100 walls of the adjacent partitions 10, thus to effectively prevent the escape of compressed air, steam or other actuating fluid. 105

The enlargements 14 of the casing or housing are also formed with recesses 28 in which 110 are pivotally mounted at 29 swinging blades or abutments 30, which latter coact with

the pistons 21 to form a pocket for the reception of the actuating fluid and thus rotate the members 12.

One wall of each of the recesses 28 is inclined or beveled in such a manner as to produce a stop shoulder 31 adapted to receive the impact of the adjacent abutment 30 and thus limit the swinging movement thereof, there being suitable coil springs 32 seated in sockets formed in the enlargements 14 and bearing against the adjacent abutments 30 for normally and yieldably supporting the active ends of said abutments in the path of movement of the rotors 12.

Attention is here called to the fact that the inner wall of each enlargement 14 is provided with an irregular or cam face 33 which by engagement with the active ends of the swinging blades or pistons 21 serve to gradually close the latter and thus prevent injury to the same by reason of a sudden jar or vibration, which would naturally result if the pistons or blades 21 were closed abruptly. The projecting portions 34 of the rotors perform the same function with reference to the swinging blades or abutments 30, that is to say, to cause the gradual closing of said abutments when the members 12 are rotated.

The rotors 12 are preferably loosely keyed to the driving shaft 13 so as to allow a slight movement of one relative to the other, and thus prevent binding or wedging action between the parts.

When the motor is employed for operating, the bit of a pneumatic drill, an inlet pipe 35 is preferably extended across the head 8 of the casing and operatively connected with the inlet ports 15 so as to form in effect a handle by means of which the device may be readily transported from place to place. A supply pipe 36 communicates with one end of the inlet pipe 35, and is provided with a turning plug 37 or valve 37, there being a similar valve 37 in the handle 35 by means of which the supply of compressed air to the compartments 11 may be controlled at will.

The driving shaft 13 is provided with a longitudinal bore 38 in which is mounted for rotation a spindle 39, the latter being spaced from the adjacent wall of the bore 38 to permit the insertion of suitable anti-friction balls 40. The lower portion of the spindle 39 is provided with a cylindrical enlargement 41, the lower end of which is threaded at 42 for engagement with a drill shaft or bit indicated at 43.

Secured to and formed integral with the lower end of the main driving shaft 13 is a pinion 44 which meshes with the teeth of suitable gear wheels 45 mounted for rotation on pinions or studs 46 secured to the head 9 of the motor casing. The gear wheels 45 are provided with integral pinions 47 which

mesh with the teeth of an internal gear 48 keyed to the cylindrical enlargement 41 of the spindle 39, so that as the rotors 12 revolve, motion will be transmitted from the driving shaft 13 through the medium of the 70 before mentioned gearing to the drill 43 to rotate the latter.

A cap-piece 49 is preferably secured to the head 9 of the casing by the tie-bolts or fastening devices 7 for the purpose of protecting the gearing, one end of the cap being provided with an annular flange 50, the interior walls of which are threaded for engagement with a correspondingly threaded 80 plate or closure 51. The cylindrical enlargement 41 of the spindle 39 is provided with an annular lip or flange 52 spaced from the head or closure 51 to form an intermediate chamber or compartment for the reception of packing 53, there being anti-friction balls 85 or rollers 54 interposed between the flange 52 and the adjacent portion of the cap 49 for the purpose of reducing friction between the parts.

Thus it will be seen that when the cock 90 or valve 37 is opened, air under pressure will pass through the inlet ports 15 and auxiliary ports 17 to the several compartments 11, and being confined between the pistons 21 and abutments 30 will rotate the 95 rotors 12 in the direction indicated by the arrow in Fig. 3 of the drawings, the compressed air being exhausted through the ports 16 and 18 in the manner before described.

The swinging blades or pistons 21 are spaced a uniform distance apart and are so arranged that when one of the pistons has passed one of the inlet ports and become active, another piston is just passing one of the exhaust ports and becomes inactive, thus causing a smooth continuous movement of the members 12, and nicely balancing the several parts with the result that the efficiency of the motor is materially increased. 105

The rotors 12 are each preferably formed with oppositely disposed annular grooves in which are seated packing rings 50', which latter bear against the walls of the adjacent partitions and casing heads, as shown, to 110 assist in preventing leakage of the actuating fluid.

As a means for controlling the passage of air, steam or other actuating fluid to the several compartments 11, the turning plugs 112 or valves 52', are provided, one of said plugs being preferably disposed in the air inlet passage opposite each compartment, either on one or both sides of the casing, said valves being provided with angularly disposed 115 port so that when the valves are turned in one direction air is admitted to the adjacent compartments, and when the valves are turned in the opposite direction the flow of air is cut off, thus permitting any one

of the movable rotors or sections to be put into or out of commission.

In Fig. 6 of the drawings a device is shown as an ordinary stationary motor for driving different kinds of machinery. In this case the opposite ends 8' and 9' of the cylinder or casing are provided with laterally extending lugs 55 for attachment to a floor or other suitable support, said end walls being provided with cylindrical extensions 56, the interior walls of which are threaded for engagement with correspondingly threaded glands 57.

When the motor is used as a source of power for operating different kinds of machinery, the shaft 18' instead of being hollow to permit the insertion of the spindle 39, as illustrated in Fig. 2 of the drawings, is made solid throughout its length, the opposite ends of the shaft 18' being extended through the glands 57 to permit the attachment of suitable wheels or pulleys, by means of which motion may be transmitted from the motor to the machinery to be operated. The inlet pipe 35' also preferably extends vertically of the casing instead of horizontally thereof, the construction and operation of the device being otherwise similar to that shown in Figs. 1 to 5 inclusive of the drawings.

It will of course be understood that the casing may be made in different sizes and shapes, and that any number of rotors may be secured to the driving shaft without departing from the spirit of the invention.

Having thus described the invention what is claimed as new is:—

1. A motor including a casing having inlet and exhaust ports, a driving shaft, a rotor secured to the shaft, a manually operated valve seated in the casing for controlling the admission of fluid to the rotor, an inlet pipe extending across one end of the casing and communicating with the inlet ports, and a valve seated in said inlet pipe for controlling the flow of fluid independently of the first mentioned valve.

2. A motor including a casing having inlet and exhaust ports, a hollow driving shaft, a rotor secured to the driving shaft, an inlet pipe extending across one end of the casing and connected with the inlet ports, a solid spindle mounted for rotation in the hollow shaft, means for transmitting motion from the hollow shaft to the spindle, a manually operated valve seated in the casing for controlling the admission of fluid to the rotor, and a second valve arranged in the inlet pipe for controlling the flow of fluid to the first mentioned valve.

3. A motor including a casing having inlet and exhaust ports, a hollow driving shaft,

a rotor secured to the driving shaft, an inlet pipe extended across one end of the casing and connected with the inlet ports, a pinion mounted for rotation with the hollow shaft, studs secured to the casing, gear wheels mounted for rotation on the studs and provided with pinions, said gear wheels meshing with the pinion on the hollow shaft, an internal gear keyed to the spindle and meshing with the teeth of the pinions on the gear wheels, and a manually operated valve seated in the casing for controlling the supply of actuating fluid through the inlet pipe to the rotor.

4. A motor including a casing having inlet and exhaust ports and provided at one end thereof with a threaded cap, a hollow driving shaft having one end thereof spaced from the cap, a rotor secured to the driving shaft, anti-friction balls interposed between the hollow shaft and cap, a spindle journaled in the hollow shaft and spaced from the latter, anti-friction balls interposed between the spindle and the adjacent end of the hollow shaft, an inlet pipe extending transversely across the casing and having its intermediate portions spaced from the casing and its opposite ends connected with the inlet ports, means for controlling the admission of fluid to the inlet ports, and means for transmitting motion from the hollow shaft to the spindle.

5. A motor including a casing having inlet and exhaust ports, a hollow driving shaft journaled within the casing and having its lower end provided with a pinion, a rotor keyed to the shaft, a valve seated in the casing for controlling the admission of fluid to the rotor, an inlet pipe extending across one end of the casing and connecting the inlet ports, a spindle mounted for rotation in the hollow shaft and having its lower end provided with an enlargement having a laterally extending flange, studs secured to the casing, gear wheels mounted for rotation on said studs, said gear wheels being provided with pinions, an internal gear meshing with the pinions of the gear wheels and keyed to the cylindrical portion of the spindle, a cap forming a housing for the gearing and provided with an internally threaded flange, anti-friction balls interposed between the flange of the spindle and said cap, and a removable plate engaging the threads on the cap and spaced from the flange on the enlargement to form a gland.

In testimony whereof I affix my signature in presence of two witnesses.

CHARLES J. OLSON. [L.S.]
